UNITED STATES PATENT OFFICE.

GEORGE LEHMAN, OF CHICAGO, ILLINOIS.

SOFA-BED.

1,191,323.

Specification of Letters Patent. Patented July 18, 1916.

Application filed April 24, 1915. Serial No. 23,662.

To all whom it may concern:

Be it known that I, GEORGE LEHMAN, a citizen of the United States, and a resident of Chicago, in the county of Cook and State 5 of Illinois, have invented certain new and useful Improvements in Sofa-Beds, of which the following is a specification.

This invention relates to those devices which are susceptible of a double purpose 10 or use, that is, devices which may be converted from the form best adapted for use as a bed into the form which is best adapted for use as a sofa.

The objects of this invention are to obtain 15 a device of the kind described which is simple in construction, easily understood and operated, not liable to break or get out of order, which can be quickly converted from one of its forms into the other one thereof, 20 and in which a considerable quantity of bed clothing can be stored.

Additional objects are set forth in the description and claims.

In the drawings accompanying and forming 25 a part hereof Figure 1 is a front elevation of a sofa bed embodying the invention, the several parts being in position to use the device as a sofa. Fig. 2 is an end elevation of the device, the several parts being in 30 the same position as in Fig. 1. Fig. 3 is a vertical section, on line 3—3 of Fig. 1, viewed in the direction indicated by the arrows. Fig. 4 is a view on line 4—4 of Fig. 1, viewed in the direction indicated by the 35 arrows, and illustrating the movable parts of the device in end elevation, with said parts in position for use as a bed. Fig. 5 is a perspective of the movable parts of the device removed from the stationary parts 40 thereof. Fig. 6 is a perspective of the upper end of the stationary part of the device. Fig. 7 is an end elevation of the inner side 45 or face of one of the ends of the stationary part of the device. And Fig. 8 is an end view of a movable head board, in a vertical plane; said board being illustrated in Fig. 5 in a substantially horizontal plane.

A reference character applied to designate 50 a given part indicates said part throughout the several figures of the drawing, wherever the same appears.

A is a stationary frame, which comprises 55 ends *a*, table *a*¹, back *a*², clip or support *a*³, and receptacle *B*. Ends *a* are attached to receptacle *B* by bolts *C* and nuts *C*¹. I make nuts *C*¹ of the kind known as butterfly

nuts, so that said nuts and bolts are removable, to permit separation of said ends and receptacle, for shipping purposes.

D is the cover to receptacle *B*, and is pivotally attached thereto by hinges *d*.

E is an abutment which is rigidly secured to receptacle *B* by screws *e*.

The table *a*¹ is mortised, as at *F*, and the ends *a* are provided with the tongues *f* (forming tenons), which fit into mortises *F*, and *G* are removable pins which fit in holes provided therefor in table *a*¹ and tenons *f*, to rigidly secure said table and ends together.

H are casters on ends *a*.

I is upholstering on cover *D*, forming the sofa seat.

J are the handles which form, when the device is converted into its bed form, legs 75 supporting the side of cover *D*.

The movable parts of the device, in addition to the cover *D*, comprise the combined back and base *K*, bed frame *L*, arms *M*, (attached to frame *K* and bed frame *L*, respectively, by pivots *m*), mattress *N*, head board *O*, foot board *O*¹, side board *O*², and springs *P*.

k are handles on the combined back and base *K*. Springs *P* are attached at the ends thereof to receptacle *B*, as at *p*, and to side board *O*², as at *p*¹, respectively. Said attachment to side board *O*² is below rod *Q* on which said board turns.

*P*¹ are springs which are attached to the end boards *O*, *O*¹, respectively, and to frame *L*.

*q*¹ are brackets, and said head and foot boards are respectively mounted on pivots *q* and brackets *q*¹. Brackets *q*¹ are secured 95 on frame *L*.

The manner in which the side board *O*² is mounted causes springs *P* to yieldingly maintain said side board in a substantially vertical plane when the bed of the device is in a horizontal plane, as is illustrated in Fig. 4, and to yieldingly maintain said side board at an angle to a horizontal plane, and pressing upward against the lower edge of the mattress *N* when said mattress is in a vertical plane, as is illustrated in Fig. 3. The manner in which the head and foot boards *O*, *O*¹, are respectively mounted and attached to the springs *p*¹, tends to yieldingly hold said boards in a horizontal plane, 105 when the bed is down, and when said boards are turned into a vertical plane, with said

bed down, to hold them yieldingly in said vertical plane. This is effected by the carrying of the end of said springs which is attached to the said boards from one to the 5 other side of the pivots *q*.

R are abutments on the head board O and footboard O¹, respectively, and when said boards are in a vertical plane, with frame K and bed frame L in a horizontal plane, 10 said abutments are in front of the front edge of the ends *a*, and said frames cannot be raised from a horizontal plane until said boards are turned from their vertical positions toward a horizontal position.

15 S are pivots which are secured to bed frame L, and *t* are castings which are secured to ends *a* of stationary frame A. Castings *t* are respectively provided with slots T and said pivots S rest in said slots to form the 20 fulcrums on which the frame L may be turned from a vertical to a horizontal position and back.

When the combined back and base K is in a substantially vertical plane it forms the 25 back of the sofa seat which is obtained by the upholstering I on cover D, and the front of said back and base is suitably finished for a sofa back. When said combined back and base K is in a horizontal plane it forms a 30 base resting on the upper edges of the receptacle B and cover D, and at said time supports, (by means of arms M) the bed frame L.

It will be observed, by reference to Fig. 3, 35 that when bed frame L is in a substantially vertical plane the combined back and base K is supported thereby, practically hanging therefrom on arms M, (the position of said arms being near a vertical plane), and when 40 said back and base K and bed frame L are in a horizontal plane said arms are in substantially a vertical plane. This is effected by the said frame K being lowered on to the abutment E in the turning of frame L 45 down on pivots S, and said abutment E forcing said frame K forward from the time when said frame rests on said abutments.

Pivots S are removably mounted in slots T of casting *t* to permit the removal of bed 50 frame L from stationary frame A.

To convert the device from the sofa form illustrated in Fig. 1 to the bed form, the cover D is turned into the position which is 55 illustrated in Fig. 4, any bed clothing which is stored in receptacle B which is required to be used in making up the bed is removed therefrom; the frames K and L are turned down into substantially a horizontal plane, as is illustrated in said Fig. 4, and the foot 60 and head boards are turned into a substantially vertical plane. The bed is then made in the ordinary way of making beds.

To convert the device from the bed form 65 to the sofa form, some or all of the bed clothing is removed therefrom, the foot and

head boards are turned down into a substantially horizontal plane, the frames K and L are turned on pivots S into a substantially vertical plane, and (the desired bed clothing having been deposited in receptacle B), 70 the cover D is closed on to said receptacle.

When the device is in the sofa form the cover D prevents frames K and L turning down from the position thereof which is 75 illustrated in Fig. 1.

I claim:—

1. In a sofa bed, a stationary frame, a bed pivotally mounted in said frame, arms pivotally mounted on said bed, a frame pivotally mounted on said first named frame adapted to support said pivotally mounted frame and to change the relative position of said bed and pivotally mounted frame when said bed and last named frame are turned from a vertical 80 to a horizontal position.

2. In a sofa bed, a stationary frame, including a receptacle to which the sides of said frame are rigidly attached, a cover to said receptacle, means to pivotally mount 90 said cover on said receptacle, and handles on said cover adapted to form legs supporting one side thereof when said cover is turned on its pivots to open said receptacle, in combination with a bed pivotally mounted in 95 said stationary frame, arms pivotally mounted on said bed, an additional frame pivotally mounted on said arms and abutments on said receptacle adapted to support said pivotally mounted frame in a pre-determined position when said bed is in a vertical plane, and said pivotally mounted frame adapted to rest on the upper edges of 100 said receptacle and cover, when said cover is turned to open said receptacle, and said 105 arms adapted to support said bed spaced above said additional frame when said pivotally mounted frame is resting on said cover and receptacle.

3. In a sofa bed, a stationary frame comprising ends, a receptacle between said frame ends and means to attach said frame ends to said receptacle, in combination with a bed frame pivotally mounted on said frame ends, a cover pivotally attached to said receptacle, an additional frame, arms pivoted to said bed frame and to said additional frame, said cover adapted to maintain said additional frame in a substantially vertical plane when said cover is closed on said receptacle and to form a support for said additional frame when said cover is opened from said receptacle, and abutments on said receptacle adapted to force said additional frame into a pre-determined position relative to said bed frame as said bed frame is turned on its pivots. 110

4. In a sofa bed, a stationary frame, a bed, a mattress to said bed pivots attaching said bed to said frame, a rail pivotally attached 115

to one side of said bed, and springs attached at one end to said rail and at the other end to said frame, said springs adapted to force said rail into position against the mattress on said bed when said bed is in a substantially vertical plane, and into position away from said mattress when said bed is in a horizontal plane.

5. In a soft bed, a stationary frame comprising ends, a bed, pivots to attach said bed to said frame, a foot board and a head board respectively attached to the head rail and to the foot rail of said bed, said boards

adapted to be turned into planes parallel to, and at right angles to said bed, means to 15 yieldingly hold said boards in said planes and abutments on said boards arranged to come in front of said ends when said bed is in a horizontal plane and said boards are at right angles thereto to latch said bed in 20 said horizontal plane.

GEORGE LEHMAN.

In the presence of—

CHARLES TURNER BROWN,
EDWARD G. JACKER.
